RAIL-ANCHOR TIE-PLATE.

1,226,136.

Specification of Letters Patent. Patented May 15, 1917.

Application filed August 25, 1916. Serial No. 116,896.

To all whom it may concern:

Be it known that I, ARTHUR L. STANFORD, a citizen of the United States, residing at Chicago, county of Cook, and State of Illinois, have invented certain new and useful Improvements in Rail-Anchor Tie-Plates, of which the following is a specification.

The present invention has to do with a combined rail anchor and tie plate for use 10 in connection with railroad road beds. It is well understood that, owing to the travel of locomotives and rolling stock along the rails, as well as on account of temperature changes, there is a very strong tendency 15 for the rails to creep or travel generally in the direction of the traffic.

The present invention has to do with a construction of tie plate which also serves 20 as a gripping device for securely gripping 25 and holding the rail, thus simultaneously performing the function of a tie plate and rail anchor. The arrangement which will be disclosed herein is very simple in its construction and application to the rail, and 30 can be manufactured at a very low cost, as compared to practically all forms of rail anchor. Furthermore, said construction can be manufactured at a cost which will be only slightly more than the cost of the tie 35 plate itself. Therefore, by the use of the invention to be herein disclosed the benefits of both a tie plate and a rail anchor construction may be secured at a cost very closely approximating the cost of the tie 40 plate itself.

Inasmuch as the use of tie plates is becoming more and more universal, not only on curves, but also on straight runs of track, it follows that by the use of the combined 45 tie plate and rail anchor to be herein disclosed, the rails may be locked or anchored at great frequency along the length of the railroad without substantially changing in any way the present tendency toward the universal employment of tie plates. In order for a device of this kind to come into favor and find wide application in the art, it must be so designed that it can be manufactured cheaply and without materially 50 departing from the present practice in the manufacture of devices of this kind. It is a very general practice to manufacture tie plates by a rolling operation. Therefore, in order for a combined rail anchor and tie 55 plate to find extensive application, it should be so designed that it may be readily manu-

factured by a rolling operation; and in this connection it should be so designed that the rolling operation may be performed by the use of rolls of little, if any, more complexity 60 and cost than the rolls which are ordinarily used in the manufacture of tie plates.

Certain objects of the present invention are to provide a construction which will substantially conform to all of the requirements 65 above discussed, while at the same time performing its functions as a rail anchor with a very high degree of efficiency and permanency.

Other objects and uses of the invention 70 will appear from a detailed description of the same which consists in the features of construction and combinations of parts hereinafter described and claimed.

Referring to the drawing:

Figure 1 shows a vertical cross section 75 through my improved rail anchor tie plate, and through the base of the rail to which it is applied, showing also in fragmentary section a portion of the tie on which the rail 80 anchor tie plate is mounted. Fig. 1 is a section taken on the line 1-1 of Fig. 2, looking in the direction of the arrows:

Fig. 2 is a plan view corresponding to Fig. 1, a portion of the spring block being 85 broken away so as to show the construction of the same in section;

Fig. 3 is an end view of the device, the set-screw and spring block being removed;

Fig. 4 is a plan view of the spring block, 90 showing the same with its initial curvature; and

Fig. 5 is a plan view of another form of spring block.

In carrying into effect the rail anchoring 95 feature of the present invention, I make use of what I will term a spring block, one of the functions of which is to bear against the base portion of the rail so as to compress the said base portion against another suitable portion 100 of the tie plate to thereby frictionally grip the base portion of the rail and thus resist any tendency for the rail to move across the face of the tie plate. This spring block is compressed against the base portion of the rail by means of a set-screw, or other suitable instrumentality, which may be under the control of the track foreman, or other operator, so that the amount of compression 105 may be controlled or adjusted in the first instance, and so that the amount of said compression may be predetermined with a fair 110

degree of accuracy. This will make it possible to estimate very closely the rail anchoring ability of each rail anchor tie plate, and will also make it possible to readily change the anchoring grip from time to time.

Referring now to the several figures, I shall first describe the construction shown in Figs. 1 to 4 inclusive, and shall then consider the construction shown in Fig. 5. The tie plate in its entirety is designated by the numeral 5. Inasmuch as the rail anchoring ability of the device will necessarily be limited by the friction of the tie plate on the tie plus the shearing strength of the spikes, it is desirable to give the tie plate as large a frictional engagement with the tie as possible. Consequently I have shown the said tie plate as being provided with a series of longitudinally extending ribs 6 in its lower portion, which ribs will embed themselves to a greater or less degree in the upper portion of the tie 7. It will be understood that, as far as the features of the present invention are concerned, the tie plate may or may not be provided with ribs or corrugations, or other tie engaging devices on its lower portion. I have also illustrated the tie plate as having a plurality of longitudinally extending ribs 8 on its upper portion, which ribs carry or support the base portion 9 of the rail 10. These ribs may or may not be used in association with the other features of my invention, but I will presently explain wherein, in some cases, they bear a peculiar relationship to other features of the invention.

While I have shown the features of my invention as applied to the particular form of tie plate mentioned, still it will be understood that the application of the said features of the invention is not limited to this or any other particular form of tie plate.

On one side of the tie plate, I make provision for compressing a spring block against the base portion of the rail. In the particular construction illustrated, this compressing means takes the form of a set-screw or the like, and in said construction I have provided an upstanding lug 11 through which the set-screw is threaded.

The said lug is shown as being formed at one side of the tie plate, and as being perforated and threaded for the reception or accommodation of the set-screw 12. On the other side of the tie plate, I provide a suitable abutment for the other side of the base of the rail, and in the particular construction illustrated, this abutment takes the form of an upstanding shoulder 13 which extends clear across the tie plate and serves to abut the entire length of the base of the rail which rests on the tie plate. The abutment 13 and the lug 11 are so spaced as to accommodate the full width of the base of the rail, and leave, adjacent to the lug 11, a substantial clearance for the accommodation of the spring

block 14. This spring block is initially formed with a slight degree of curvature on its face which abuts against the face of the rail, so that upon applying a heavy pressure to the spring block, the said block may yield as it is compressed against the rail, thus effecting the said compression under resiliency. By effecting the compression under resiliency, there will be assurance that the base of the rail will at all times be under pressure, notwithstanding expansion and contraction which may take place with variations of temperature both in the rail base and in the tie plate, and there will also be assurance that the rail base will be under compression at all times notwithstanding the jarring and vibrations which accompany the travel of rolling stock along the rail. Inasmuch as the spring block bears in a resilient manner against the set-screw, it follows that the said set-screw will always be under a resilient pressure, so that the spring block will tend to lock the set-screw at all times, and thus prevent unthreading, due to jarring of the rail and tie plate.

In the particular construction illustrated in Figs. 1 to 4 inclusive, the spring block is shown as being initially provided with a slight degree of concavity in its face which engages the rail base. This fact is well illustrated in Fig. 4, wherein it will be observed that there is a clearance 15 between the engaging face of the spring block and the line 16 which represents a straight face. The spring block is also shown as being provided with a boss or the like 17 adapted to receive the end of the set-screw 12, so that the pressure of the set-screw is directly applied to the spring block at that point where it will be most advantageous in compressing the block against the rail base. Reference to Figs. 1 and 2 will show the manner of application of the spring block to the rail base, and the manner in which the spring block may be straightened out upon the application of a sufficient pressure by the set-screw. The amount of pressure thus exerted is not limited by the amount of compression necessary to straighten out the spring block, for it is evident that even after the resiliency of the spring block has been completely taken up, a further pressure may be applied by the set-screw, which pressure will be directly transmitted to the rail base through the medium of the block. However, even in this case there will always be assurance that the rail base will be under compression notwithstanding variations of temperature and vibrations, because if there were to occur a separation between the abutment 13 and the end of the set-screw sufficient to remove the aforementioned direct pressure, still the spring would, by reason of its resiliency, follow such separation and

maintain the rail base under compression. It will also be observed that the resiliency of the spring block will also serve the additional function of taking up any wear which may occur from time to time, so that the parts will always be under spring pressure.

The amount of flexure in the spring block will be determined by the initial clearance to be taken up by compression. Frequently the clearance 15 will approximate one-eighth to three-sixteenths of an inch in actual practice. This, however, is a matter of degree and will depend upon the particular size of the spring block, the material of which it is made, its modulus of elasticity, etc.

The spring block is conveniently formed with a longitudinally extending recess or channel 18 for the accommodation of the edge of the base of the rail. This construction will insure that the rail base will be properly socketed and registered with respect to the spring block at all times. The amount of this recess is shown in Fig. 4, by means of the dotted lines. Inasmuch as the spring block is channeled, it follows that a suitable space or clearance should be provided beneath the edge of the rail base for the accommodation of the lip 19 of the spring block. Such clearance may be provided in any suitable manner, but in the particular construction illustrated, the ribs 8 serve, among others, the function of supporting the rail base at a sufficient elevation to provide a necessary clearance for the accommodation of the lip portion 19 of the spring block.

Manifestly the abutment 13 may take any suitable form, its function being to resist sidewise movement of the rail base, and simply, as a matter of convenience, I have shown the said abutment as being fixed with respect to the tie plate 5, and as being directly engaged by the rail base.

It will be observed from examination of Fig. 3 in particular, that the lug 11 is provided with a gradual slope on each of its end faces. By reason of this fact, it is possible to roll the said lug in the tie plate, so that the device may be manufactured by a steel rolling operation, and at very low cost.

In the arrangement thus far described, the spring block is provided with a concave face for contact against the rail base, and the resiliency is secured by pressing inwardly on the central portion of the block, so as to straighten out this face. In the arrangement shown in Fig. 5 on the contrary, the face which bears against the rail base is convex in form, and means are provided for straightening out the spring block by pressure on its end portions. In the construction shown in Fig. 5, the convex face

20 bears against the rail base, and is suitably channeled, if desired, to accommodate the edge of the rail base. In the construction shown in this figure, there are provided two bosses 21 and 22 for the accommodation of two set-screws, one at each end of the spring block. It will be quite evident that upon applying pressure to the end portions of the block shown in Fig. 5, a resilient pressure will be exerted on the edge 75 of the rail base, thus giving an anchoring action very similar to that which has been previously described.

I desire to point out the fact that the holding power of my device as a rail anchor 80 is added to and acts in unison with the frictional resistance, due to the contact, under pressure, of the rail base on the tie plate.

While I have herein shown and described only certain forms of construction embodying the features of my invention, still it will be understood that I do not limit myself to the said constructions except as I may do so in the claims.

I claim:

1. A device of the class described comprising, in combination, a tie plate having on one side an abutment for engaging one side of the base of a rail, and having on its other side an abutment for the accommodation of a set-screw, the said abutments being separated a sufficient distance for the accommodation of the base of the rail and for the provision of a space between the last mentioned abutment and the adjacent edge of 100 the base of the rail, a spring block located in said space, said spring block having a curved face adjacent to the edge of the rail base, and a set-screw threaded into the adjacent abutment and engaging the spring 105 block for the purpose of compressing the same against the base of the rail.

2. A device of the class described comprising, in combination, a tie plate having on its upper portion a pair of abutments, one of said abutments preventing movement of the rail base away from the other abutment, and the abutments being separated a sufficient distance to provide a space between the other abutment and the base of 115 the rail, a spring block located in said space, said spring block having a curved face adapted for engagement against the adjacent edge of the rail base, and a set-screw threaded through the adjacent abutment 120 and engaging the spring block to compress the spring block against the rail base.

3. A device of the class described comprising, in combination, a tie plate having on its upper portion a pair of abutments, one of said abutments serving to prevent movement of the rail base away from the other abutment, the abutments being separated a sufficient distance to provide a space between the rail base and the last mentioned 125 130

- 4
- abutment, a spring block located in said space, said spring block having a curved face adapted to engage the adjacent edge of the rail base, and means under the control of the operator for exerting a force between the last mentioned abutment and the spring block for the purpose of compressing the spring block against the edge of the rail base.
- 10 4. A device of the class described comprising, in combination, a tie plate having on its upper portion a pair of abutments, one of said abutments serving to prevent movement of the rail base away from the other abutment, the abutments being separated a sufficient distance to provide a space between the rail base and the last mentioned abutment, a spring block located in said space, said spring block having a curved face adapted to engage the adjacent edge of the rail base, and means for exerting a force between the last mentioned abutment and the spring block for the purpose of compressing the spring block against the edge of the rail base.
- 15 5. A device of the class described comprising, in combination, a tie plate having on its upper portion a pair of abutments, one of said abutments serving to prevent movement of the rail base away from the other abutment, the abutments being separated a sufficient distance to provide a space between the rail base and the last mentioned abutment, a spring member located in said space and bearing against the adjacent edge of the rail base, and means under the control of the operator for exerting a force between the last mentioned abutment and the spring member for the purpose of compressing the latter against the edge of the rail base.
- 20 6. A device of the class described comprising, in combination, a tie plate, an abutment upstanding from the tie plate and, bearing against one edge of the rail base, a spring member bearing against the opposite edge of the rail base, and means connected with the tie plate and under the control of the operator for exerting a force against the spring member for the purpose of compressing the same against the edge of the rail base.
- 25 7. A device of the class described comprising, in combination, a tie plate having an abutment upstanding therefrom and bearing against one of the edges of the rail base, a spring member positioned to exert pressure against the other edge of the rail base, and screw means connected with the tie plate and under the control of the operator for applying pressure to the spring member.
- 30 8. A device of the class described comprising, in combination, a tie plate having on its upper surface a pair of abutments, one of said abutments serving to limit the movement of the rail base away from the other abutment, the abutments being separated a sufficient distance to provide a space between the last mentioned abutment and the adjacent edge of the rail base, the surface of the tie plate being depressed at a point inside of said last mentioned abutment to cause the edge of the rail base to overhang the surface of the tie plate, a bowed spring block located intermediate the last mentioned abutment and the edge of the rail base and provided with a channel engaging said rail edge, and means for exerting a pressure between the spring block and the abutment for holding the spring block into close engagement with the edge of the rail.
- 35 9. A device of the class described comprising, in combination, a tie plate having on its upper surface a pair of abutments, one of said abutments serving to limit the movement of the rail base away from the other abutment, the abutments being separated a sufficient distance to provide a space between the last mentioned abutment and the adjacent edge of the rail base, a bowed spring block located intermediate the last mentioned abutment and the edge of the rail base and provided with a channel engaging said rail edge, and means for exerting a pressure between the spring block and the abutment for holding the spring block into close engagement with the edge of the rail.
- 40 10. A device of the class described comprising, in combination, a tie plate having on its upper surface a pair of abutments, one of said abutments serving to prevent movement of the rail base away from the other abutment, the abutments being separated a sufficient distance to provide a space between the rail base and the last mentioned abutment, a bowed spring block located in said base and having its convex face in engagement with the adjacent edge of the rail base, and screw means carried by the last mentioned abutment for exerting a pressure against the concave face of the block for affording spring compression between the block and the edge of the rail base.
